UNITED STATES PATENT OFFICE

2,574,019

LIGHTING FIXTURE FOR ELONGATED
TUBULAR LAMPS

William P. Crockett, Jr., Chicago, Ill.

Application November 29, 1948, Serial No. 62,477

6 Claims. (Cl. 240—51.11)

1

This invention relates to a lighting fixture, and particularly to a fixture for fluorescent lights.

In general, a fluorescent light fixture is known as a "strip," which includes an elongated rectangularly shaped box which is adapted to enclose and support what is known as the ballast, support the sockets for the light tube, and other appurtenances.

Heretofore, the strip box has been made by cumbersome and expensive methods which included cutting material to accurate dimensions, shaping the pieces in a break, and spot welding adjoining elements.

An object therefore of the present invention is the provision of a fluorescent strip box in which the above noted objections are overcome.

Another object is the provision of a fluorescent strip box which, by reason of a novel construction, can be made by punch press operations.

Another objection to previously known devices of this general type is that due to their nature two men were required to mount a fixture; their nature was such that all of the parts of a fixture were necessarily assembled before the fixture was mounted, with the result that the assembled fixture became unwieldy.

A further object of the present invention is the provision of a fixture which by reason of its novel construction, the parts may be mounted and assembled in a succession of steps, whereby its installation becomes only a one-man job.

A still further object is the provision of a fixture of the nature described in which the sockets for the light tubes are positioned flush with the end of the strip box, so that when a series of boxes are disposed in end to end abutting relationship, the light tubes form a continuous unbroken string.

With these and other objects in view, my invention consists in the construction, arrangement and combination of the various parts of my device whereby the objects contemplated are attained, as hereinafter more fully set forth, pointed out in my claims and illustrated in the accompanying drawings, wherein:

Figure 1 is a longitudinal sectional view of the device of the present invention;

Figure 2 is a top view of the device shown in Figure 1, part of the cover being broken away;

Figure 3 is a sectional view taken on line 3—3 of Figure 1;

Figure 4 is an exploded view of a portion of the strip box and the attachments used in connection therewith;

2

Figure 5 is a view taken on line 5—5 of Figure 4;

Figure 6 is a view taken on line 6—6 of Figure 4; and

Figure 7 is a top view of one end of the cover for the strip box.

Referring in detail to the drawings, the device is shown in Figure 1 as it would be viewed when handled by a person. However, when the device is attached to a ceiling it would be in inverted position and the interpretation of the following description may be made accordingly. The device may be mounted on a ceiling as mentioned above and, of course, it may be mounted on a wall or any other surface as its final position would be oriented according to the surface on which it is mounted.

The device includes what is known as a fluorescent strip box 12 which is in the shape of an elongated rectangular box. The strip box 12 includes a floor portion 14, side walls 16, and end walls 18. The side and end walls are formed integral with the floor 14 in a manner to be presently described. The end walls 18 have bent-over portions 20 which abut against the inner surface of the ends of the adjacent side walls 16. The upper end of each overlapping portion 20 is provided with a notch 22 and a lug 24 is formed on each end of each side wall 16 and is bent over and clamped in the respective notch 22. The side and end walls are thus held in upright rigid position with respect to the floor. Formed integral with each end wall 18 is a pair of laterally spaced tongues 26 extending inwardly from the end walls across the open side of the box which, of course, is opposite the floor 14. The tongues 26 have a peculiar shape as evidenced in Figures 4 and 5 following the contour of the upper marginal edges of the end walls.

The tongues 26 of each pair have horizontal portions 28 directed toward each other. The floor 14 of the strip box has a portion embossed as indicated at 30, extending toward the open side of the box. The embossed portion 30 is provided with stamped holes 32 for receiving threaded metal screws. The numeral 34 represents knock-out portions which are formed in the various elements of the box in the usual manner. The knock-out portions 34 are severed from the material of the box nearly completely around their periphery, being held in place only by a small dimension connecting piece. Holes 36 are stamped in the floor 14 for securing the box to a supporting surface.

As stated in the introduction, one of the most important objects of the invention is the pro-

vision of a fluorescent strip box which can be fabricated by punch press operations. Metal strip of the desired width is obtained in rolls and cut to the desired length by a stamping or punch press operation. The segment thus cut off is also in the same operation cut in outlined form to the shape having the desired elements to make up the completed box. In the next step the side and end walls are turned upwardly and this may also be done by a punch press operation. Finally, the lugs 24 are turned in and clamped in the position shown in Figures 2 and 4.

From the above it will be seen that an economical box structure is accomplished by means of simple punch press operations and I wish to point out its contrast with previous known types of boxes used for fluorescent lighting. Previously, strips were measured accurately to the proper dimensions, then placed in a break and finally the elements making up the box were spot welded together. Such procedure, it will be readily recognized by those skilled in the art, results in an expensive article.

Sockets for supporting the light tube are indicated at 38. One such socket is mounted at each end of the strip box and each socket includes a lower block portion 40 and an upstanding portion 42 which is adapted to receive one end of the light tube indicated at 44. The upper end of the portion 42 is provided with a socket opening 46 having an open channel 48 and studs 50. Spring contacts 52 are arranged on opposite sides of the studs 52. The light tube 44 is provided with a pair of prongs which can be inserted through the channel 48 and are finally positioned one above and one below the studs 50. The tube is then rotated bearing against the contacts 52 and spreading them apart so that the contacts are biased inwardly against the prongs in the light tube. The contacts 52 extend down through the interior of the socket where they are provided with connector means 54, such as screws for securing light wires thereto. The front vertical surface of the block portion 40 is provided with a vertical slot 56 and intermediate the ends of the slot 56 is a horizontal slot 58.

The means for securing the sockets 38 in position include clamp members 60 and 62. The clamp member 60 (Figures 1 and 4) includes a pair of laterally spaced horizontal legs 64 and a lower shorter horizontal leg 66 interconnected by a web portion 68. The legs 64 and 66 are provided with tapped holes so as to receive a screw 70. The web portion 68 extends downwardly below the lower leg 66 and is provided with outwarded horizontal lugs 72 to which is secured a starter socket 74. The starter socket 74 is provided with a socket opening 76 in the bottom of which are a pair of bayonet slots 78 in which are mounted contact elements. The contact elements are connected with connector elements such as indicated at 80 for connection with light wires.

The clamp member 62 is similar to the clamp member 60 except that the extension of the web 68 and the lugs 72 are omitted.

Figure 4 shows to best advantage the method and means by which the socket 38 is mounted. The clamp (60 or 62) and socket 38 are fitted together so that the leg 66 of the clamp is inserted in the horizontal slot 58 in the socket and the upper legs 64 are positioned slightly above the block portion 40 and on opposite sides of the upstanding portion 42. The two elements together,

namely the clamp and the socket, are fitted on the pair of tongues 26 so that the upper legs 64 engage the portions 28 of the tongues 26 and the block portion 40 of the socket engages the under-surface of the tongues. The screw 70 is then turned down and the socket and clamp are both held securely by friction on the tongues 26. It should be noted here that the socket 38 abuts against the inner surface of the end wall so that the socket may be considered flush with the end of the strip box. The socket and the clamp 62 in the opposite end are mounted in place in the same manner. After both sockets are put in position the light tube 44 is inserted in a manner referred to above.

The strip box is covered by a cover member 82 which is formed by a punch press operation. The cover, of course, follows the contour of the upper edge of the end walls 18. Each end of the cover 82 is provided with a cut out portion 84 in which is a slot 86 disposed centrally of the cover and opening outwardly. The cover is also provided with a hole 88; together with other holes or knock outs 90 for securement of the louvre thereto. The hole 88 is disposed in register with the starter socket 74 so that a starter 92 can be inserted into the starter socket. The starter 92 has conventional prongs for fitting into the bayonet slots 78 and contacting the contacts therein.

The reference numeral 94 represents diagrammatically what is known as ballast which includes a transformer and other appurtenances common to fluorescent lighting. The ballast 94 is positioned on the embossed portion 30 and held in place by metal screws 96 which are threaded into the holes 32. The embossed portion and the holes therein enable the ballast to be applied after the box is secured to the ceiling. Nuts cannot be applied when the box is in position, but this is rendered unnecessary since the holes are effective for holding the screws. It will be noted that the screws do not extend any farther than the plane of the main portion of the floor.

In addition to the economy in manufacturing due to the novel structure of the device, there is also another greatly advantageous feature. This feature resides in the fact that the device can be easily and readily installed by a single workman. In installing the device the empty strip box, stripped of all the appliances—namely, the cover, sockets and clamps and the ballast, is applied to the intended supporting surface; for example, the ceiling, and secured thereto such as by means of screws inserted through the holes 36 in the floor 14. The box itself is light and the workman can easily hold it with one hand and secure it in position with the other hand. Next, the ballast 94 is secured in position. This also can easily be done by one person. Next, the sockets 38 are put into position and clamped as described above. In the assembling operation the screws 70 are not tightened down at this point. The next step is to apply the cover 82. This can easily be done by sliding the slot or notch 86 over the screw 70 on one end and without then tightening down the screw the other end is fitted in place. In the case of the opposite end, the screw 70 is not yet in place and after the cover is seated the screw is turned in and tightened. Then the screw 70 in the first end is tightened. The cover 82 and the sockets 38 are then all tightened in final position.

After the foregoing has been done the starter 75 92 is inserted through the hole 80 and then into

the starter socket. Thereafter, the light tube 44 is inserted in place.

Fluorescent strips such as the final assembly just described, as known, may be placed end to end to form a long lighting fixture. In such a case the sockets 38 in successive strips are in substantial abutting relationship with the effect that the light tubes in successive strips form a continuous string.

While I have herein shown and described a preferred embodiment of my invention, manifestly it is susceptible of modification and rearrangement of the parts without departing from the spirit and scope thereof. I do not therefore wish to be understood as limiting my invention to the precise form herein disclosed, except as I may be so limited by the appended claims.

I claim as my invention:

1. In a device of the character described, a box having a floor, side walls, end walls, and an open side opposite the floor, each end wall having a pair of laterally spaced tongues extending over the open side, a socket associated with each pair of tongues, each socket having a portion positioned between the respective tongues, whereby each socket is slideable with respect to the tongues into engagement with the end wall, each socket having a portion extending from the box from the open side thereof, each socket having a block portion extending inwardly from its end wall in vertical register with a portion of the tongues, said block portion having a vertical groove in its inner surface, and clamp means for each socket, each clamp means having vertically spaced fingers adapted to fit over and engage said block portion and said tongues, and screw means interconnecting said fingers for forcing the fingers toward each other and thereby clamping the sockets to the respective pairs of tongues, said screw means being fitted in said groove.

2. In a device of the character described, a box having a floor, side walls, end walls, and an open side opposite the floor, each end wall having a pair of laterally spaced tongues extending over the open side, a socket associated with each pair of tongues, each socket having a first portion positioned between the respective tongues and extending from the open side of the box, whereby each socket is slideable with respect to the tongues, each socket having a second portion of greater width than the spacing between said tongues, said second portion extending inwardly into the box from the open side of said box, said second portion being in register with a portion of the tongues, whereby movement of the socket outwardly from the box is restricted, and spaced clamping members engaging the second portion of said socket and said tongues for securing the socket to the tongues.

3. In a device of the character described, a box having a floor, side walls, end walls, and an open side opposite the floor, each end wall having a pair of laterally spaced tongues extending over the open side, a socket associated with each pair of tongues, each socket having a first portion positioned between the respective tongues and extending from the open side of the box, whereby each socket is slideable with respect to the tongues, each socket having a second portion of greater width than the spacing between said tongues, said second portion extending inwardly into the box from the open side of said box, said second portion being in register with a portion of the

tongues, whereby movement of the socket outwardly from the box is restricted, a bracket associated with each socket and having a first portion engaging the pair of tongues and a second portion engaging said second portion of the socket, a securing member cooperating between the two said portions of the bracket to clamp the socket and the tongues together, and one of said brackets having a lug affixed thereto, and a starter socket mounted on said lug.

4. In a device of the character described, a box having a floor, side walls, end walls, and an open side opposite the floor, each end wall having a pair of laterally spaced tongues extending over the open side, a socket associated with each pair of tongues, each socket having a first portion positioned between the respective tongues and extending from the open side of the box, whereby each socket is slideable with respect to the tongues, each socket having a second portion of greater width than the spacing between said tongues, said second portion extending inwardly into the box from the open side of said box, said second portion being in register with a portion of the tongues, whereby movement of the socket outwardly from the box is restricted, a removable bracket associated with each socket and having two portions, one bracket portion engaging the second portion of the socket and the second bracket portion engaging the respective tongues, a securing member for biasing said portions of each bracket toward each other to clamp the second portion of the socket and the tongues together, and a cover for fitting over the open side of the box, said covering having an opening at each end adapted to receive respective ones of said securing members, said securing members being adapted to secure the cover to the box.

5. In a device of the character described, a box having a floor, side walls, end walls, and an open side opposite the floor, each end wall having a pair of laterally spaced tongues extending over the open side, a socket associated with each pair of tongues, each socket having a first portion positioned between the respective tongues and extending from the open side of the box, whereby each socket is slideable with respect to the tongues, each socket having a second portion of greater width than the spacing between said tongues, said second portion extending inwardly into the box from the open side of said box, said second portion being in register with a portion of the tongues, whereby movement of the socket outwardly from the box is restricted, a removable bracket associated with each socket and having a pair of clamping fingers engaging the tongues and the second portion of said socket, the tongues being disposed between one of said clamping fingers and the second portion of said socket, and a securing member biasing said clamping fingers of each bracket toward each other to clamp the second portion of the socket and the respective pair of tongues together.

6. In a device of the character described, a box having a floor, side walls, end walls, and an open side opposite the floor, each end wall having a pair of laterally spaced tongues extending over the open side, a socket associated with each pair of tongues, each socket having a first portion positioned between the respective tongues and extending from the open side of the box, whereby each socket is slideable with respect to the tongues, each socket having a second portion of greater width than the spacing between said tongues, said second portion extending inwardly

into the box from the open side of said box, said second portion being in register with a portion of the tongues, whereby movement of the socket outwardly from the box is restricted, a bracket associated with each socket and having a first portion engaging the pair of tongues and a second portion engaging said second portion of the socket, and a securing member cooperating between the two said portions of the bracket to clamp the socket and the tongues together. 10
